UNITED STATES PATENT OFFICE.

JOHN F. DUSTIN, OF FULTON, NEW YORK.

LOOM.

1,112,366.

Specification of Letters Patent. Patented Sept. 29, 1914.

Application filed September 5, 1911. Serial No. 647,790.

To all whom it may concern:

Be it known that I, JOHN F. DUSTIN, a citizen of the United States, residing at Fulton, county of Oswego, State of New York, have invented an Improvement in Looms, of which the following description, in connection with the accompanying drawing, is a specification, like characters on the drawing representing like parts.

10 This invention relates to looms and particularly to looms of that type employing a shifting shuttle box, and the object of the invention is to provide a novel loom-stopping mechanism which is rendered operative whenever the shifting shuttle boxes bring a shuttle into operative position at a time while another shuttle is also in operative position on the lay.

15 In the operation of a drop box loom it sometimes happens that through faulty mechanism the shifting shuttle boxes will bring a shuttle into position to be thrown across the lay by the picking mechanism while the shuttle which has previously been 20 in operation is still occupying a position on the lay or is boxed at the opposite end of the lay, and when this condition arises the presence of two shuttles in position on the lay will cause a smash or some other injury 25 to the loom or fabric being woven.

30 My invention aims to prevent such a catastrophe by providing means for stopping the loom whenever two shuttles are simultaneously in position to be thrown 35 across the lay by the picking mechanism.

35 I have illustrated herein a construction embodying my invention which will demonstrate the principle thereof, it being understood, of course, that the constructional 40 details may be varied without departing from the invention.

45 Figure 1 is a vertical section through a loom having my improvements applied thereto. Fig. 2 is a section on the line $x-x$, Fig. 1, showing the lay and the harnesses in front elevation; Fig. 3 is a view showing the operation of the loom-stopping mechanism; Fig. 4 shows the shuttle detecting mechanism; Fig. 5 is a detail view of a 50 portion of the knock-off mechanism.

I have shown in the drawings a loom having a frame 1, a breast beam 2, a lay 3 which is supported on the lay swords 4, a

crank shaft 6 which is connected to and which operates the lay through a connecting 55 rod 7, a shipper lever 8, and a knock-off lever 9. These parts are or may be of any well-known construction and as they form no part of the present invention I do not deem it necessary to give any further description thereof.

The loom shown is of the drop box type and the lay 3 has at one end a shuttle box 10 provided with the usual binder 11 and at the other end a set of shifting shuttle boxes 65 12, each of which is also provided with a binder 13. As stated above, it sometimes happens in the operation of a loom of this type that the shuttle boxes will bring a shuttle 14 into position to be thrown across 70 the lay 3 while another shuttle 15 is still boxed in the shuttle box 10, and when this occurs the presence of either shuttle in its shuttle box will, of course, prevent the other shuttle from being properly boxed when it 75 is thrown across the lay, and the failure of said shuttle to be boxed will cause a smash or some other damage.

In the present embodiment of my invention I have provided an electrically-controlled loom-stopping mechanism which operates to stop the loom when the above condition arises and thereby prevent any damage. The electric loom-stopping mechanism herein shown comprises a circuit normally 80 open at two points, means to close the circuit during the movement of the lay at one point when the shuttle is boxed in the shuttle box 10 and at the other point when a shuttle is boxed in one of the shifting shuttle 85 boxes, so that the circuit will be completely closed whenever a shuttle occupies each of the shuttle boxes, as shown in Fig. 2, and means operated by the closing of the circuit to actuate the knock-off lever 9 thereby to 90 stop the loom.

17 designates the usual protector rod which is provided with the fingers 16 that engage the binders 11 and 13 respectively. Loosely mounted on the protector rod 17 at 100 each end thereof is a shuttle detector in the form of an arm 19 provided with a portion 18 that is adapted to engage the binder 11 or 13. Each shuttle detector 19 is acted on by a spring 20 which encircles the protector 105 rod and operates to hold the detector against

- the binder. Each detector 19 carries at its lower end a wiper contact 21, said contacts being insulated from the other parts of the loom in some suitable way. As herein illustrated each contact is provided with a stem 22 which enters and is secured to a sleeve 23 of insulating material that in turn is secured to a projection 24 rigid with the detector arm 19.
- 10 Each contact 21 coöperates with a pair of contacts or terminals 25 that are insulated from each other in some suitable way as by being sustained by a support 74 of insulating material, but are situated in an electrical circuit of the loom-stopping mechanism. As herein shown one contact of one pair of contacts 25 is connected to or grounded on the loom frame by a wire 26 and the other contact of said pair is electrically connected to one of the contacts 25 of the other pair by a wire 27. The other contact of said latter pair is connected by a wire 28 to a magnet 29, and the latter is connected by a wire 30 to a battery 31 or other source of electrical energy, said battery being connected in turn to the loom frame.
- 15 The wiper contacts 21 are carried by the lay and therefore during the movement of the lay they pass over the contacts 25. The construction is such, however, that neither contact 21 will engage its contact 25 except when a shuttle is in the box. When there is no shuttle in the box and the binder consequently is in its inmost position the spring 20 will throw the shuttle detector forwardly into the full line position, Figs. 1 and 4, and thus carry the corresponding contact wiper 21 into such a position that it will pass over the contacts 25 as the lay vibrates without engaging said contacts. When a shuttle enters the box, however, said shuttle will force the binder outwardly thereby swinging the detector arm 19 into the position shown by dotted lines Figs. 1 and 4, and when the arm 19 occupies this position the contact 21 is thrown into such a position that it will contact and have a wiping engagement with the contacts 25 when the lay moves backwardly.
- 20 From the above it will be seen that during the normal operation of the loom first one contact 21 and then the other is brought into engagement with the contacts 25 as the lay vibrates. Since the circuit is closed alternately at the contacts 25, however, the loom-stopping mechanism does not operate under ordinary circumstances. If, however, for any reason a second shuttle 14 is brought into operative position while the shuttle 15 is still in the box 10, then upon the next operation of the lay the circuit will be closed at both pairs of contacts 25, and when this occurs the magnet 29 is energized thereby to operate the knock-off lever 9 and thus effect the stopping of the loom.

Various mechanisms may be employed for operating the knock-off lever 9 when the magnet 29 becomes energized. As herein shown the armature 32 for said magnet is carried by a lever 33 which is pivoted at 34 to an arm or bracket 35 that is carried by the loom frame and preferably insulated therefrom. The lever 33 has connected to one end thereof a link 36 which is also connected to a lever 37 that is pivoted at 38 to a longitudinally-extending rod or member 39 which is connected at 40 to an arm 41 and operates in a guide 49. This arm is pivoted to the loom frame at 42 and is adapted to engage the knock-off lever 9.

43 is a dog which is pivoted at 44 to the bar or member 39, said dog having a nose 45 which is adapted to be engaged by an extension 46 formed on the end of the lever 37. Said dog is also provided with a tail 47 which is adapted to be engaged by a hook 48 fast on one of the law swords whenever the loom-stopping mechanism is operated.

Under normal conditions when the magnet is deenergized, the weight of the parts holds said parts in the position shown in Fig. 1, in which position the tail 47 of the dog is below the path of movement of the hook 48 so that during the vibration of the lay said hook does not engage said tail. Whenever the magnet 29 is energized, however, the armature 32 will be drawn downwardly, thus swinging the lever 33 and raising the lever 37, which operation causes the extension 46 to act against the nose 45 of the dog thereby to swing the tail of the dog upwardly into position to be engaged by the hook 48, as seen in Fig. 3. The dog is so situated that when the tail thereof is raised the hook 48 will engage said tail just after the lay begins its rearward movement, and the engagement of said hook with the dog will draw the member 39 backwardly, thus operating the knock-off lever and stopping the loom. The dog is so situated that this operation of stopping the loom will occur before the shuttles are thrown, or at least before the lay beats up again, so that there is no danger of a smash occurring.

While it would be within my invention to connect the battery 31 directly to the loom frame, yet I prefer to interpose in the circuit an additional circuit breaker which will maintain the circuit open during the forward movement of the lay so as to prevent the circuit from being closed by the contacts 21 except when the lay is moving backwardly. This additional circuit closer is shown as a wiper 50 fast on the crank shaft 6 and adapted to engage a spring contact 51 which is connected by a wire 52 with the battery 31, said contact being carried by the loom frame, but insulated therefrom, as at 53. The wiper 50 has a semi-circular shape and is so arranged on the

shaft that it will be in engagement with the contact 51 when the lay is moving backwardly, but will be disconnected from or out of engagement with said contact when the lay is moving forwardly. Fig. 1 shows the crank shaft 6 on the back center with the wiper 50 just passing off from the contact 51. The member 37 is shown as having a projection 53 which is adapted to be engaged by a lug 57 on the lay sword when said member is raised by the energization of the magnet 29. I provide this construction so as to insure that the loom will be stopped if for any reason the hook 48 does not engage or slips off from the dog 43.

55 designates heddle frames of ordinary construction.

From the above it will be seen that I have provided a simple mechanism for stopping the loom whenever two shuttles accidentally come to occupy operative positions on the lay, and while I have illustrated herein one embodiment of the invention I do not wish to be limited to the constructional features shown.

Having fully described my invention, what I claim as new and desire to secure by Letters Patent is:—

1. In a loom, the combination with a lay having two shuttle boxes, of a shuttle detector associated with each shuttle box and arranged to occupy one position when a shuttle is in the box and another position when the box is empty, each shuttle detector having a wiper contact associated therewith, which contact moves in one path when a shuttle occupies the corresponding box and in another path when there is no shuttle in the box, an electric circuit having two pairs of separated stationary contacts, each pair of stationary contacts being situated to be engaged by the corresponding wiper contact when it moves in the first-named path, and means to stop the loom when the circuit is closed simultaneously by both wiper contacts.

2. In a loom, the combination with a lay having at each end a shuttle box provided with a binder, of a shuttle detector adjacent each shuttle box and operated by the binder thereof, a wiper contact associated with each shuttle detector and situated beneath the lay, each wiper contact moving in one path when a shuttle occupies the corresponding box and in another path when there is no shuttle in the box, an electric circuit having two pairs of stationary contacts situated to be engaged by the wipers when they move in the first-named paths, and means to stop the loom when the circuit is closed simultaneously at both pairs of contacts.

3. In a loom, the combination with a lay having at each end a shuttle box provided with a binder, of a shuttle detector pivoted to the lay adjacent each shuttle box, each

shuttle detector engaging the binder of its shuttle box and extending below the lay, a contact wiper sustained by the lower end of each shuttle detector, an electric circuit having two pairs of separated stationary contacts sustained by the loom frame beneath the lay, the presence of a shuttle in each shuttle box operating through the binder and shuttle detector to place the corresponding wiper contact in position to engage the stationary contacts as the lay vibrates, and means to stop the loom when the circuit is closed simultaneously at both pairs of stationary contacts.

4. In a loom, the combination with a lay having two shuttle boxes, of a shuttle detector associated with each shuttle box, a normally-open circuit having two pairs of separated stationary contacts, a wiper contact carried by each detector, each detector when actuated by a shuttle in the corresponding shuttle box moving its wiper contact into position to engage the corresponding pair of stationary contacts as the lay vibrates, and means to stop the loom when the circuit is closed at both pairs of stationary contacts simultaneously.

5. In a loom, the combination with a lay having a shuttle box at one end, of shifting shuttle boxes at the other end, a knock-off lever, a member connected thereto and extending beneath the lay, a dog pivoted to the member, a hook rigidly carried by the lay, and means to move said dog thereby to bring it into the path of the hook whenever the shifting shuttle boxes bring a shuttle into operative position while another shuttle is also in operative position.

6. In a loom, the combination with a lay having a shuttle box at one end, of shifting shuttle boxes at the other end, a hook movable with the lay, a knock-off lever, a member connected thereto and extending beneath the lay, a dog pivoted to said member and normally occupying a position out of the path of movement of said hook, and means to throw said dog into the path of movement of the hook whenever the shifting shuttle boxes bring a shuttle into operative position while another shuttle is also in operative position, said dog being so positioned as to be engaged by the hook when the lay begins its backward movement.

7. In a loom, the combination with a lay having a shuttle box at one end, of shifting shuttle boxes at the other end, a knock-off lever, a member connected thereto, a dog pivoted to said member, a hook carried by the lay, a shuttle detector associated with each shuttle box, a normally-open circuit having two pairs of separated stationary contacts, a wiper contact carried by each shuttle detector, each detector when actuated by a shuttle in the corresponding shuttle box moving its wiper contact into posi-

tion to engage the corresponding pair of stationary contacts as the lay vibrates, and means to move said dog thereby to bring it into the path of the hook when the circuit is closed at both pairs of stationary contacts simultaneously.

In testimony whereof, I have signed my

name to this specification, in the presence of two subscribing witnesses.

JOHN F. DUSTIN.
